UNITED STATES PATENT OFFICE.

ABNER S. COOK, OF BURLINGTON, IOWA.

LETTER-BOX.

SPECIFICATION forming part of Letters Patent No. 298,733, dated May 20, 1884.

Application filed February 14, 1884. (No model.)

To all whom it may concern:

Be it known that I, ABNER S. COOK, a citizen of the United States, residing at Burlington, Des Moines county, Iowa, have invented 5 a new and useful Letter-Box, of which the following is a specification.

My invention relates to letter-boxes for private use, simple in construction, made safe against rain and snow, and easily examined 10 and emptied. This I accomplish by the device hereinafter described.

In the drawing, the figure is a perspective view of my improvement.

In the drawing, A is a box, of any suitable 15 material, preferably of wood, furnished with a window, W, in front, and having its top T perforated at M to admit letters, papers, and other mail-matter.

L is a lid attached by any sort of a stiff spring 20 to the top or back of the box, (which may preferably be extended,) so as to be held down close over the top.

B is the bottom of the box A, attached to

an under extension of the box-back, if desired, by a stiff spring of any suitable kind. 25

In operating my box I raise the lid L and insert the letters or papers through M, which then drop upon the bottom B. A gentle pressure on the bottom opens the box and the matter can be taken out. 30

It is evident that the springs holding the lid L and the bottom B must be strong enough, respectively, to prevent lifting by the wind and to stand considerable momentum. It is also evident that the best construction of the 35 box-top is slanting.

What I claim, and desire to secure by Letters Patent, is—

A letter-box, A, provided with window W, 40 perforated top T, lid L, and bottom B, hinged by strong springs, substantially as and for the purpose described.

ABNER S. COOK.
